T. E. HAWKINS

RADIATOR COVER

Filed Oct. 28, 1921

UNITED STATES PATENT OFFICE.

TODD E. HAWKINS, OF HUNTINGTON, INDIANA.

RADIATOR COVER.

Application filed October 28, 1921. Serial No. 511,071.

To all whom it may concern:

Be it known that I, Todd E. HAWKINS, a citizen of the United States, residing at Huntington, in the county of Huntington and State of Indiana, have invented certain new and useful Improvements in Radiator Covers, of which the following is a specification.

My present invention, which generally 10 relates to improvements in that type of radiator covering means in which is included a front curtain or shade for fitting over the radiator front and adapted for being regulated from the car dash to wholly 15 or partly expose such front, more especially has reference to certain improvements on the radiator cover means shown and described in my copending application filed January 18, 1921, Serial No. 438,136.

20 My present invention comprehends certain improvements in the means for holding the shade or curtain member, disclosed in my pending application, to its vertically adjusted position over the radiator front 25 and my said improvements are designed for a more positive action of the tension elements and for being more economically combined with the shade or curtain portion of the cover and whereby the same can be 30 made with less expense than is possible with the coil spring devices which constitute a part of the radiator cover means described and shown in my copending application aforesaid.

35 In its more subordinate feature, my present invention embodies simple and effective devices locatable within convenient reach of the car driver whereby to hold the pulley cable or cord, by which the curtain or shade 40 is manipulated, to its drawn back curtain adjusting positions and for quickly releasing the curtain when it is desired to permit it to drop for wholly or partly exposing the radiator front.

45 With other minor objects in view that will hereinafter appear, my present invention embodies in a radiator cover of the type mentioned certain details of construction and peculiar arrangement of parts, all of

which will be hereinafter explained, specifically stated in the appended claims and illustrated in the accompanying drawings, in which:

Figure 1 is a perspective view of my present construction of radiator hood cover, 55 the shade or curtain flap being shown at a partly raised position, the pull cord or cable clamping device being also indicated.

Figure 2 is a section of the hood cover taken substantially on the line 2—2 of Figure 1, the curtain or shade being shown at the fully raised position.

Figure 3 is a detail vertical section of the lower end of the hood with the curtain at the lowermost or fully curled position.

Figure 4 is a similar view of the upper or pull end of the curtain.

Figure 5 is a detail face view of a portion of the curtain flap with one of the spring bands indicated in dotted lines.

Figure 6 is a detail section thereof, on the line 6—6 on Figure 5.

Figure 7 is a vertical section partly in elevation of the pull cord or cable clamp device.

In my present construction of radiator hood cover the same is composed of the conventional flexible material, preferably leather of suitable thickness whereby to retain its shape for being quickly placed onto 80 and over the radiator front or removed therefrom as desired.

The cover or front portion is cut out to produce a windowlike opening 1 for exposing the radiator air tubes and the edges of 85 the said opening 1 are stiffened by a sheet metal frame 2 mounted on the back of the cover and to which the edges of the cover, that surround the opening 1 are riveted or otherwise firmly secured.

The cover front adjacent the upper edge of the opening is secured to the adjacent metal rim member 20 by eyelets or other like tubular fasteners 3—3 that pass through suitable apertures 30 in the member 20 and 95 which constitute passages for the guide tubes 4 through which the pull cords or cables pass, as clearly shown in Figure 2.

of the drawings, and as presently further explained.

5 designates the leather flap which constitutes the curtain or shade member and 5 which is adapted for partly or wholly covering the opening 1, as desired, and the said shade 5, in my present construction is permanently stitched along its lower edge 50 to the front fabric, as is best shown in 10 Figure 3.

The shade 5 is of double thickness and has a plurality of longitudinally extended pockets 6-6 formed by parallel pairs of longitudinal stitching 7-7 and the upper ends 15 of the said pockets terminate at the hem 51 along the top of the shade that forms a transverse loop 52 to receive a reinforce metal strip 8 which constitutes the pull member of the shade since to it the ends 20 90 of a pair of pull cables or cords 9 are attached, as is best shown in the detail section Figure 4.

The lower end of each longitudinal pocket 6 opens through the bottom, as at 60, to 25 provide for the ready insertion of resilient metal bands 10 whose tension is such that they curl up like a watch spring.

In the practical arrangement of the tension devices for rolling up the curtain when 30 pull strain on the cords 9 is released, the said spring bands 10 are inserted through slots 11 in the turned up edge in the bottom member of the metal rim and fit into the full length of their respective pockets in the 35 curtain or shade flap.

The lowermost end of each spring metal band remains seated within the metal rim, as is shown in Figure 3, to provide a rigid connection for that end of the spring band.

40 By referring to Figures 2 and 3, it will be apparent that by pulling out the free end of the curtain the folds of the curtain unwind and thereby straighten the spring bands 10 and the curtain flap, it being obvious that 45 when pulled up to the limit, as in Figure 2, the said spring bands 10 are at their fully distended or flat position.

For uncurling the curtain and pulling it up to its wholly or partly extended position, 50 it is only necessary to apply a pull tension on the cords 9-9, that curl up with the curtain when the latter rolls up.

In my present invention, the two cords 9-9 join with a single pull cord 95 which 55 passes through a central tubular guide 12 in the car dash 15 and through a guide aperture in a handle portion 40 of a clamping device that is attached to the inside of the car dash within convenient reach of the 60 driver's hands.

The clamp device mentioned, is shown in detail in Figure 7 and comprises a plate having a channel or groove 41 to receive the pull end 96 of the cord 95, and the said 65 cord end 96 is normally held tightly clamped

against the bottom of the groove 41 by a pivoted cam 42 which has a finger manipulated handle 43 for swinging the cam 40 to the released position (see dotted lines, Figure 7).

70 44 designates a stout spring that connects the cam and the rim to which it is pivotally attached.

75 From the foregoing description, taken in connection with the accompanying drawing, the complete construction, the manner of manipulating the shade device and the advantages of my present arrangement of radiator hood will be readily apparent to automobile users.

80 The wind-up spring devices are exceedingly simple, can be readily applied to the flap 5 and when once fitted to their operative position they will be positively held to their operative condition and in shape for 85 readily rolling up the curtain flap when strain on the pull cord is removed, which operation is quickly effected without any special manipulation by the car driver, who simply presses up on the finger lever of the 90 clamping cam to release the cord end 96.

95 The cover with its curtain portion can be cheaply made and readily patterned for fitting over the particular shape of radiator front upon which it is desired to use it.

What I claim is:-

1. A cover for radiators comprising a flexible body shaped for fitting over a radiator and including a front portion having an opening and a curtain flap attached to the front and adapted for being pulled over the said opening, a metal reinforce attached to the edges of the front portion and surrounding the opening therein, a spring device cooperative with the flap, said spring device including a band spring that extends lengthwise of and is flexibly secured to the flap and whose tension normally causes it to curl up with the flap, the lowermost end of the spring band engaging the metal reinforce at the lower edge of the opening in the flap and means operable from the vehicle for unwinding the cover flap and the winding spring connected therewith and for holding the said spring and the flap at the 115 partly or wholly distended position.

2. As a new article, a radiator hood protector comprising a flexible body having front, top and side portions, the front portion having an opening adapted for registering with the entrance end of the air ducts of the radiator and a flap that constitutes a curtain, said flap being attached at its lower end to the said front portion of the flexible body along the lower edge of the opening 125 therein, a rigid metal reinforce for the edges of the said opening, the curtain flap having at least one pocket extending the full length thereof and open at the bottom, a curling spring band insertable lengthwise 130

through the bottom of the longitudinal pocket in the flap, a metal reinforce at the lower end of the opening having a slot through which the lower end of the spring band passes and in which it is retained whereby as the said band normally curls up it winds up the curtain flap with it, and a

pull cord attached to the free end of the curtain flap and adapted to be operated from a vehicle seat for drawing out the curtain flap and its winding spring, the said cord winding up with the curtain flap when the pull strain thereon is released.

TODD E. HAWKINS.
